LIQUID COAXIAL LINE AND ROTARY JOINT

Richard J. Violette, Washington, D. C.

Application October 25, 1945, Serial No. 624,617

4 Claims. (Cl. 178—44)

(Granted under the act of March 3, 1883, as
amended April 30, 1928; 370 O. G. 757)

1

This invention relates to high frequency transmission lines and, more particularly, to such lines of the concentric type having a swing joint and suitable for use for radio frequency energy at high frequencies and above.

One object of the present invention is the use of an organo-silicon polymer fluid as a dielectric medium for insulating one or more inner conductors within the outer tubular line member of a concentric transmission line system.

Another object of the invention is to provide such a transmission line in which the concentric conductors in one part may freely swivel or rotate relative to the cooperating concentric conductors of the relatively stationary part of the system, permitting corresponding movement of the coupled conductor sections, but in which such members are constantly retained in fluid-tight and leak-proof joint-forming relation.

A further object of the invention is to provide a transmission line of the above class having the above advantages and which at the same time includes compensating means whereby expansion and contraction of the liquid dielectric within the line may occur due to temperature variations incident to its operating environment without injury or displacement of the concentric conductors of the transmission line system.

These and other objects of the invention will be best understood and appreciated from the following description of a particular embodiment thereof, for purposes of illustration only, and shown in the accompanying drawings, in which:

Fig. 1 is a side elevation of the concentric transmission line in accordance with the present invention as adapted for use with high frequency radio equipment;

Fig. 2 shows an enlarged longitudinal section, in part, of the transmission line shown in Fig. 1;

Fig. 3 is an enlarged cross-sectional view taken substantially across the section-line 3—3 of Fig. 1;

Fig. 4 is an enlarged longitudinal section, in part, of the inner conductor sub-assembly showing the middle and central conductors employed in the transmission line system of Fig. 1; and

Figs. 5 and 6 are end views of the fluted insulator spacers employed for supporting the middle and central conductors, respectively.

Shipboard installation of concentric feeders and transmission lines generally associated with high frequency equipment including their antenna systems often are mounted at locations where they are required to operate at high

2

temperatures, such as is encountered by leads and feeders to antennas mounted back of smoke stacks aboard ships. If concentric leads and feeders of the solid dielectric type, i. e., in which the inner conductor is surrounded with a solid insulating material such as polyethylene, are installed in such locations the high temperatures normally encountered in the vicinity of the stack, which often run above 300° F., are sufficient to produce a considerable change in length of the solid dielectric material within such cables with consequent fracture or rupture thereof. This expansion of the solid dielectric medium also has a serious disturbing effect in that "arc-overs" often are experienced at the locations of fracture when the contraction of the solid dielectric material takes place as well as the formation of carbon traces which destroy the subsequent insulating protection afforded by the affected dielectric medium.

In the high frequency concentric line according to the present invention silicone polymer fluid such as disclosed in the Patent 2,377,689, issued June 5, 1945, to Hyde, which has a high dielectric property suitable through ranges of temperature change from -60° F. to +300° F. is employed as insulation surrounding the inner conductor. In carrying out the present invention, expansion means for compensating for displacement of the fluid dielectric due to temperature effects is provided at the end of a run of the feeder where it is connected to one or more antennas. The expansion compensating means in a preferred arrangement in accordance with this invention comprises expansion bellows secured to the coupling fitting at the end of the feeder run and provides an expansion chamber for the overflow or axial displacement of the fluid dielectric which fills the rotating unit.

Referring now to Fig. 1 in detail, there is shown a concentric rotary joint transmission line in accordance with the present invention that is particularly adapted for use with a liquid dielectric. The line system comprises a length of concentric line generally designated 10 having an outer conductor 12 and a middle or intermediate conductor 13, both being tubular and formed of brass, copper or other good conducting material; and a central conductor or metal rod 14 which is coaxial with the conductors 12 and 13 supported in this position by suitable dielectric spacers or beads (not shown) within the middle conductor 13. The lower end of the outer tubular conductor 12 is terminated in a T-pipe fitting 15 which carries a coaxial tuning

40

45

50

55

55

stub 16 having an external tubular conductor 17 forming an axial extension of the middle tubular conductor 13 within the line 10 and enclosing an inner rod (not shown) along its axis constituting an axial extension of the central rod 14 of the line 10. In proximity to the tuning stub 16 and at substantially right angles thereto is positioned a concentric stuffing tube 18 by means of which the inner and outer conductors of a coaxial cable (not shown) are connected to the middle tubular conductor 13 and the outer tubular conductor 12, respectively, of the guide 10.

The upper end of the guide 10 is terminated in a hollow cross-pipe fitting 20 formed with four 90° tubular pipe-connector stubs 21, 22, 23 and 24, respectively, the pipe stub 21 being suitably affixed to the upper end of the outer tubular conductor 12, as by soldering or otherwise. The cross-pipe 20 mounts on its pipe stubs 22 and 24 the coaxial tuning stub 25 and the concentric stuffing tube 26 respectively, both of which are positioned at right angles to the main guide line 10, while on the pipe stub 23 there is positioned in axial coincidence with the axis of the guide 10 an expansion compensator device generally designated 28 which forms one important feature of the present invention and whose detailed construction and operation will be hereinafter described.

As shown in greater detail in Fig. 2, the concentric tubular conductors 12 and 13 and the central rod 14 of the guide 10 are connected respectively through appropriate resiliently fingered contact sleeves 31, 31a and 31b respectively of a coaxial swing joint 30, which will be described hereinafter in somewhat greater detail, to the corresponding tubular conductors 32 and 33 and the central rod 34 of the upper or movable portion of the line system. The conductors 32, 33 and 34, as thus joined together form rotatable axial extensions of the corresponding stationary conductors 12, 13 and 14. The middle tubular conductor 33 and the central rod 34 project into the interior of the cross-pipe 20 and make substantially a right angle connection with the middle tubular conductor 35 and the central rod 36, respectively, positioned coaxially of the tuning stub 25. Also the middle tubular conductor 33 and the outer tubular conductor 32 of the rotary part of the guide system is connected respectively to the inner conductor 38 and the other metallic braided conductor 39 of the cable 40 by means of which the output from one of the antennas (not shown) is fed to the coaxial pair of conductors 32, 33 and, in turn, through the rotary joint to coaxial conductors 12, 13 of the line system. To this end, the middle tubular conductor 33 is connected by means of metallic insert 41 and resilient contact sleeve 42 to the inner conductor 38 of the cable 40, while the outer tubular conductor 32 is connected through pipe stubs 21 and 24, metallic housing 43 and associated coupling insert 44 and lock device 45 to the outer metallic braid 39 of the cable 40.

The tuning stubs 17 and 25 are similar in construction, and both are connected to the same coaxial pair of conductors constituting a part of the guide 10. Suitable coaxial coupling connectors 46 and 47 are provided at the outer terminal ends of the tuning stubs 25 and 17 respectively so that the stub 25 may be connected onto the output cable of a second antenna (not shown) and the stub 17 of the lower portion of the rotary line unit may be connected onto a suitable input cable

(not shown) to an external circuit device such as, for example, a receiver and/or an indicator outside the pedestal mount supporting the line system.

Referring to Fig. 1 again, there is shown a rotary or swing joint 30 of the concentric type which is positioned in the main run of the guide 10 intermediate the cross-pipe 20 and the T-pipe 15, this swing joint being of a known construction in the electrical art adapted for enabling rotational movement of the conductors 32, 33 and 34 carried by the upper portion of the guide system affixed to the cross-pipe 20 with respect to the corresponding stationary part of these concentric conductors enclosed within and forming the guide 10. One type swing joint of the aforementioned character which has been found satisfactory for this purpose is the so-called Chiksan rotary joint for electrical connectors manufactured by the Chiksan Tool Company, Brea, California. More specifically, there is disclosed in Patent No. 2,369,849 to Dwight M. Phillips, granted February 20, 1945, a rotary joint of this general character designed for use with tubular electrical conductors of a concentric line system.

Briefly described, the Chiksan swing joint 30 employs a ball bearing rotary portion 48 to which is suitably attached the movable concentric conductor selections 32, 33 and 34 for providing rotary or swivel connection thereof to the corresponding stationary conductors 12, 13 and 14 of the guide 10, as shown in Fig. 2. The cylindrical stationary portion 49 of the swing joint 30 carries a circular flange 49 by means of which the joint and guide system may be attached to suitable support such as, for example, the antenna pedestal.

The transmission line system 10 including the joint 30 and a part of the tuning stubs 17 and 25 is filled with a silicone polymer fluid, one type of which is manufactured by the Dow-Corning Company. The silicone fluid preferably is an organo-compound of silicon in which the skeleton of the compound is an oxygen chain having organic radicals directly connected to the silicon atoms. The fluid is characterized further by having a substantially flat viscosity curve, high dielectric capacity, and thermal stability.

In order to prevent the silicone oil from leaking out of the line 10 suitable seals 50 and 51 are provided in the tuning stub 25 and stuffing tube 26 respectively, such seals being preferably of rings of live gum rubber mounted within a suitable clamping device, as is shown in Fig. 2. Similarly, the tuning stub 17 and the stuffing tube 18 each are provided with the above-described sealing arrangements.

In order that the silicone oil can insulate the middle tubular conductors 13, 33 and 35 from their respective central rods 14, 34 and 36, suitable holes 53 are provided in the side walls of these middle conductors, see Fig. 4, so that the silicone oil in the cylindrical space surrounding these middle conductors and their respective enclosing outer tubular conductors can flow inside the middle conductors around the central rods 14, 34 and 36 respectively. The polyethylene spacers 55 and 56, see Figs. 4, 5 and 6, for insulatingly supporting for the middle tubular conductors and their central rods, respectively, are shown as comprising annular disc members having a plurality of longitudinal partially circular flutes at spaced intervals in their outer peripheries to permit the silicone oil to flow freely axially along the major portion of the full length of line system including

the swing joint in filling. Since the silicone oil or fluid has high dielectric constant it effectively insulates the insulator spacers 55 and 56 and their associated conductors.

In Fig. 2 there is shown in sectional elevation details of the expansion compensator device 22 which comprises a hollow cylindrical can 60 open at its bottom end and closed at its top end, as at 61, the bottom open end portion of the can tightly fitting over and being attached by screws 62 to the annular closure member 63 which in turn is sweated onto or otherwise united in a fluid-tight fashion to the outer end portion of the pipe stub 23. Provided in the upper face of the closure disc 63 is an annular reentrant groove 64 which receives and anchors one end of the flexible expandible metal bellows 65. The other end of this bellows is provided with a metal lid 66 having a centrally apertured insert 67 closed by a bleed plug 68 which has screw threaded connection therewith. It will be evident from the foregoing description that any longitudinal displacement or flow of the silicone fluid from the line system into the interior of the bellows 65 as would occur in response to the expansion of the fluid due to the high temperatures normally existing in the vicinity of its installed location will be followed by appropriate expansion of the bellows 65 and thus compensate for this change in volume of the liquid dielectric.

As thus constructed it will be seen that the transmission line provided is one which may be readily assembled and disassembled and that it, at the same time, is adapted to accommodate for any volume changes incident to expansion and contraction of the dielectric fluid which may occur due to temperature and weather variations without any likelihood of buckling or other injury to the line components. The middle and central conductors also are sufficiently insulated from the outer conductors to withstand any high voltage which it may be desired to transmit through the line yet at the same time permitting rotational movement of the upper part of the line, as desired.

In one practical application of the invention the main part of the line including the rotary joint under electrical tests showed a corona onset at 30,000 volts.

While various metal combinations may be employed to provide spring contact at the friction surfaces of the concentric sleeve members forming the rotary joint 30 it was found that certain metal combinations when used with Dow-Corning silicone fluid #200 (polymethyl siloxane or polymerized methyl silicone) as a lubricant and a dielectric material in the rotary joint assembly, wore excessively with noticeable flaking and metallic particle sludge contamination. The preferred metal combination showing minimum wear and contamination effect in Dow-Corning #200 silicone fluid was found to be silver tipped fingers on the sleeves 31, 31a and 31b respectively, spring contact of the silver fingers being effected at a friction surface on hardened steel. This silver-steel rotary frictional combination showed no noticeable sludge at 200,000 revolutions at 100 R. P. M., and the silver fingers of the rotary parts taking on a slight polish after 500,000 revolutions.

It will now be clear from the foregoing description that a thoroughly practical and durable liquid rotary coaxial joint and transmission line construction has been provided which is capable of operating efficiently and in which the several objects hereinabove mentioned, as well as many others now apparent are accomplished.

As many changes could be made in the above construction and many apparently different embodiments of this invention could be made without departing from the scope thereof, it is to be understood that all matter hereinabove set forth in the above description or shown in the accompanying drawings, shall be interpreted as illustrative and not in a limiting sense, and that no limitations upon this invention are intended other than are imposed by the scope of the appended claims.

The invention described herein may be manufactured and used by or for the Government of the United States of America for governmental purposes without the payment of any royalties thereon or therefor.

What is claimed is:

1. In combination, a concentric transmission line comprising outer, intermediate and central metallic conductors, a rotary concentric joint located intermediate the ends of said line, said joint including outer, intermediate, and central concentric fingered sleeve members respectively interconnecting the outer, intermediate, and central conductor of each end of said line and adapted to permit relative rotation of the corresponding line conductors at either side of said joint while maintaining the electrical continuity of said outer, intermediate and central conductors throughout the length of said line, the rotary joint and associated concentric lines being filled with a liquid polymerized silicone to provide a lubricant for the joint and a dielectric for the line, the fingered portions of said sleeves being of silver and having frictional engagement with hardened steel contact surfaces on said conductors, and means for compensating for expansion of said liquid when subjected to temperature ranges from -60° F. to +300° F., said compensating means comprising an adjustable bellows at one end of said line and responsive to the axial flow of the displaced liquid therein incurred by being subjected to such variable temperature conditions.
2. In combination, a rotary joint including outer and inner concentric fingered sleeve members, and a concentric transmission line having sections at either side of said rotary joint and coaxial therewith, each of said line sections comprising an outer metallic tubular conductor and an inner metallic conductor, the outer fingered sleeve member having telescopic frictional connection with the adjacent end portions of the outer conductors of each line section establishing electrical connection therebetween for rotational motion, the inner fingered sleeve member having telescopic frictional connection with the adjacent end portions of the inner conductors of said line sections to maintain electrical connection between said inner conductors for rotational motion, the rotary joint and associated concentric lines being filled with a liquid polymerized silicone to provide a lubricant for the joint and a dielectric for the concentric lines, the fingered contact portions of said sleeves being of silver and having frictional engagement with hardened steel contact surfaces on said respective outer and inner conductors.
3. A high frequency transmission line comprising an inner and an outer tubular metallic conductor and a central metallic rod all concentrically arranged with respect to each other, a concentric rotary joint located intermediate the ends of said line in the main run thereof and containing rotary connectors for said outer and

inner tubular conductors and said central rod, a hollow junction fitting at one end of said line, said junction fitting being of conducting material and having a plurality of tubular pipe stubs thereon, a concentric tuning stub having inner and outer tubular metallic conductors and a central rod, the outer tube of said tuning stub being secured to one of said pipe stubs and the inner conductors of said tuning stub being connected within said junction fitting to the intermediate and central conductors respectively of body portion of said line, means for connecting the outer conductor of a two-conductor cable to another of said pipe stubs of the junction fitting, means within said junction fitting for connecting the inner conductor of the aforementioned two-conductor cable to the intermediate conductor of the body portion of said transmission line, a liquid dielectric medium surrounding the intermediate and central conductors of said line, and means for compensating for expansion and longitudinal displacement of said dielectric liquid when it is subjected to temperature ranges from -60° F. to $+300^{\circ}$ F., said compensating means being mounted on the third pipe stub member of said junction fitting and comprising an adjustable metallic bellows in communication with the interior of said hollow junction fitting and arranged for flow of the displaced dielectric liquid therein as will occur when said dielectric liquid is subjected to the aforesaid variable temperature conditions.

4. In combination, a rotary joint including outer and inner concentric fingered sleeve members, and a concentric transmission line having sections at either side of said rotary joint and coaxial therewith, each of said line sections com-

prising an outer metallic tubular conductor and an inner metallic conductor, the outer fingered sleeve member having telescopic frictional connection with the adjacent end portions of the outer conductors of each line section establishing electrical connection therebetween for rotational motion, the inner fingered sleeve member having telescopic frictional connection with the adjacent end portions of the inner conductors of said line sections to maintain electrical connection between said inner conductors for rotational motion, the rotary joint and associated concentric lines being filled with a liquid polymerized methyl silicone to provide a lubricant for the joint and a dielectric for the concentric lines, the fingered contact portions of said sleeves being of silver and having frictional engagement with hardened steel contact surfaces on said respective outer and inner conductors.
